COMBINED WHATNOT AND STAND FOR A
TELEVISION OR THE LIKE

Adam G. Miller, Williamsport, Pa.

Application February 24, 1955, Serial No. 34,649

Term of patent 14 years

(Cl. D33—3)

Fig. 1 is a front elevational view of a combined whatnot and stand for a television or the like;

Fig. 2 is a side elevational view of the article; and
Fig. 3 is a top plan view thereof.

I claim:

The ornamental design for a combined whatnot and stand for a television or the like, as shown.
